[57] CLAIM

The ornamental design for a bread slicing guide, substantially as shown and described.

DESCRIPTION

FIG. 1 is a front perspective view of a bread slicing guide showing my new design;

FIG. 2 is a front elevational view thereof;

FIG. 3 is a rear elevational view thereof;

FIG. 4 is a top plan view thereof;

FIG. 5 is a side elevational view thereof looking from the right in FIG. 1; and

FIG. 6 is a bottom plan view thereof.

The side opposite that shown in FIG. 5 is a mirror image thereof.

FIG. 1

FIG. 2

FIG. 3

FIG. 4

FIG. 5

FIG. 6
